UNITED STATES PATENT OFFICE

152,760

DESIGN FOR A SAW HANDLE

Frank Weaver, Indianapolis, Ind., assignor to E. C. Atkins and Company, Indianapolis, Ind., a corporation of Indiana

Application March 6, 1947, Serial No. 137,391

Term of patent 14 years

(Cl. D93—4)

To all whom it may concern:

Be it known, that I, Frank Weaver, a citizen of the United States, residing at Indianapolis, in the county of Marion and State of Indiana, have invented a new, original, and ornamental Design for a Saw Handle, of which the following is a specification, reference being had to the accompanying drawing, forming a part thereof.

Fig. 1 is a side elevational view of a saw handle, showing my new design;

Fig. 2 is a top plan view thereof;

Fig. 3 is a sectional view taken substantially on the line 3—3 of Fig. 1 and looking in the direction of the arrows; and

Fig. 4 is a sectional view thereof taken substantially on the line 4—4 of Fig. 1 and looking in the direction of the arrows.

I claim:

The ornamental design for a saw handle, as shown.

FRANK WEAVER.
